ERNEST U. MACK, OF FLORENCE, SOUTH CAROLINA.

AIR-BRAKE DEVICE.

1,153,806.

Specification of Letters Patent. Patented Sept. 14, 1915.

Application filed January 9, 1915. Serial No. 1,331.

To all whom it may concern:

Be it known that I, ERNEST U. MACK, a citizen of the United States, and a resident of Florence, in the county of Florence and State of South Carolina, have invented certain new and useful Improvements in Air-Brake Devices, of which the following is a specification.

My invention relates to the air-brake systems on railways, and the object thereof is to provide means under the control of the engineer of a train for retaining the air pressure in the brake cylinders of the cars of the train while the auxiliary reservoirs thereunder are being re-charged, thereby securing greater safety in handling trains on grades, and also securing greater economy in the use of air and dispensing with the services of the train hands or brakemen for the purpose.

My invention is fully described in the following specification, of which the accompanying drawings form a part, in which like reference characters are used to designate like parts in each of the views, and in which:—

Figure 1 is a side view of a locomotive and one car of a train, broken away, with my invention shown thereon in a diagrammatic manner; Fig. 2 is an enlarged, fragmentary, view of only such parts as constitute the basis of the invention; Fig. 3 is a sectional view taken through a conventional auxiliary reservoir to illustrate the 35 operation of my device; and Fig. 4 is a modification of the train signal line air actuated piston mechanism shown in the preceding figures.

In Fig. 1 I have shown, fragmentarily, a locomotive cab 4 having the main reservoir 5 thereunder, and a car 6 having the auxiliary reservoir 7, brake cylinder 8, and triple-valve 9 thereunder, and also the train signal pipe 10 passing throughout the length of the train and having the usual couplers 11 between the units of said train; the train-line pipe 12 is connected with the triple-valve, as is also the pipe 13 and valve 14 of the particular car.

Beneath each car of the train I provide a casing 15 having a rod 16 guided therein and which rod carries three pistons 17, 18, and 19, dividing the casing into four compartments 20, 21, 22, and 23, the first of which is in communication with the train signal pipe 10 by means of a pipe 24; the

second, 21, is in communication with the outer air by means of ports 25; the third is in communication with the exhaust port 26, Fig. 3, of the triple-valve by means of a pipe 27 which has a branch pipe 13 therein carrying the pressure retaining valve 14; and the fourth is in communication with the outer air by means of ports 30 and the vent 30^a; these means of communication described obtain when the pistons are in their lowermost position shown in Fig. 2, and into which position they are moved by means of a spring 31, this being the positions of the pistons when the auxiliary reservoirs are being re-charged and the pressure being retained in the brake cylinders.

Within the cab 4 is a three-way valve casing 32 having a valve 33 therein provided with a passage 34 adapted to connect the train signal pipe 10 with either of two pipes 35 and 36, both branches from the main reservoir pipe 37, the former through a reducing valve 38 and a safety-valve 39, and the latter through a reducing valve 40, the reducing valve 38 and the safety-valve 39 being set for a pressure of thirty-five pounds and the valve 40 for forty-five pounds in the form shown, although this difference of pressure is merely for the purpose of description.

When the valve 33 is set in the position shown the pressure of thirty-five pounds is not sufficient to overcome the resistance of 90 the spring 31 in the casing 15 under each car, and the air from the triple-valve exhaust port 26 is confined within the compartment 22 thereof, these casings and pistons constituting the pressure retaining valves for the 95 units of the train, and now being operative, no air being permitted to escape therefrom under any train unit but, if desired, the trainman may release this pressure for any one train unit by opening the valve 14.

To return the parts to normal position, with the pistons in the positions indicated by dotted lines in Fig. 2, the engineer throws the valve 33 to the opposite side whereby the main reservoir is connected with the 105 train signal pipe and with all of the pressure retaining valve casings 15 through the reducing valve 40 set at forty-five pounds pressure; this pressure is sufficient to overcome the resistance of the spring 31 and the 110 pistons are moved into their alternate positions, thus placing the triple-valve exhaust

pipe in communication with the ports 30 and with the outer air, this occurring beneath each unit of the train, and the brake cylinders are thus exhausted of air, and the pistons therein may be returned to normal positions by their springs.

When the engineer, by means of the valve 33, changes the connection of the train signal pipe 10 from the higher pressure reducing valve 40 to the lower pressure reducing valve 38, the safety-valve 39 reduces the air pressure in the train signal pipe very gradually through the restricted vent 39^a in the safety-valve, so preventing a false signal from the signal whistle.

It will thus be seen that I utilize the train signal pipe for producing the desired result on the air-brake system and without any interference at all with the latter, and that the engineer has the exhaust of air from the brake cylinders under control at all times, and for every unit of a train, and without calling upon the trainmen to release the brakes, and he may throw his brake valve, not shown, into position to release the brakes and yet maintain the pressure in the brake cylinders while he is re-charging the auxiliary reservoirs.

The vents 25, as will be understood, are to permit the escape of the air from the compartment 21 and also serve to prevent the leaking of air from the air-brake system to the signal system, and vice versa. Attention is also drawn to the gasket 17^a on the piston 17 which makes a sealed or air-tight joint when the pistons are in their normal, or uppermost, positions.

In the structure shown in Fig. 4 the piston 19 is replaced by means of a cone valve 40 also numbered 19 as the full equivalent thereof, and the piston 18 is dispensed with. Air admitted to the under side of the piston 17 forces it upwardly, if the pressure is sufficiently high to overcome the spring 31, to move the valve out of its normal interposed position between the pipe 27 from the triple valve exhaust port and the exhaust ports 30 of the casing 15. The operation of this form is identical with the form already described, and the same reference characters have been used to identify the parts of one with the equivalents of the other.

Having fully described my invention, what I claim as new, and desire to secure by Letters Patent, is:—

1. The combination with the air-brake system of a railway train having a brake cylinder and an auxiliary reservoir under each unit in operative connection throughout the train, of a train signal pipe, a low pressure reducing valve therein, a high pressure reducing valve therein, a valve adapted for communication with either reducing valve, and means operable by the air passing through said high pressure valve for

exhausting the air from said brake cylinders.

2. The combination with the air-brake system of a railway train having a brake cylinder and an auxiliary reservoir under each unit in operative connection throughout the train, of a train signal pipe, a low pressure reducing valve therein, a high pressure reducing valve therein, a valve adapted for communication with either reducing valve, and a valve automatically actuated by the air passing through said high pressure valve for exhausting the air from said brake-cylinders.

3. The combination with the air-brake system of a railway train having a brake cylinder and an auxiliary reservoir under each unit in operative connection throughout the train, of a train signal pipe, a low pressure reducing valve therein, a high pressure reducing valve therein, a valve casing, in constant communication with said brake cylinders, a piston in said casing adjacent to the point of said communication, a supplemental piston, and a rod connecting the same with said first named piston, said casing being provided with exhaust ports adapted to be placed in communication with said brake cylinder exhaust when said piston is moved from normal position by the air through said high pressure valve, to exhaust the air from said brake cylinders.

4. The combination with the air-brake system of a railway train having a brake cylinder and an auxiliary reservoir under each unit in operative connection throughout the train, of a train signal pipe, a low pressure reducing valve therein, a high pressure reducing valve therein, a casing in communication with said valve and with said brake cylinders, and provided with exhaust ports adjacent to the point of communication with said brake cylinders, a piston normally arranged between the point of communication with said brake cylinders and with said casing exhaust ports, a supplemental piston in operative connection with said first named piston adapted to be actuated by the air through said high pressure reducing valve to move said first named piston beyond said exhaust ports, whereby said brake cylinders may be exhausted, and means for returning said pistons to normal positions when said low pressure reducing valve is placed in communication with said casing.

5. The combination with the air-brake system of a railway train having a brake cylinder and an auxiliary reservoir under each unit in operative connection throughout the train, of a train signal system, a low pressure reducing valve therein, a high pressure reducing valve therein, a valve adapted for communication with either reducing valve, means operable by the air passing

through said high pressure valve for exhausting the air from said brake cylinders, and a manually operable retaining valve interposed between said brake cylinders and 5 said air-operated exhausting means.

6. The combination with the air-brake system of a railway train having a brake cylinder and an auxiliary reservoir under each unit in operative connection through- 10 out the train, of a train signal pipe, a low pressure reducing valve therein, a high pressure reducing valve therein, a valve adapted for communication with either reducing valve, means for exhausting the air from 15 said brake cylinders when said valve is placed in communication with said high pressure reducing valve, and means for preventing the exhaust of air from said brake cylinders when said valve is in communica- 20 tion with said low pressure reducing valve.

7. The combination with the air-brake system of a railway train having a brake

cylinder and an auxiliary reservoir under each unit in operative connection throughout the train, of a train signal pipe, a low 25 pressure reducing valve therein, a high pressure reducing valve therein, a valve adapted for communication with either reducing valve, means operable when said valve is in communication with said high pressure reducing valve for exhausting the air from 30 said brake cylinders, means operable when said valve is in communication with said low pressure reducing valve for preventing such exhaust, and means for preventing the 35 leakage of air from said train signal pipe through said means.

In testimony whereof I have signed my name to this specification in the presence of two subscribing witnesses.
